FEEDING DEVICE

Theodore G. McGirr, Brooklyn, N. Y.

Application May 24, 1928. Serial No. 280,158

5 Claims. (Cl. 51—215)

My invention relates to automatic feeding device, having particular reference to the feeding of solders containing a plurality of pieces of steel, such as are used for safety razor blades, or for splitting silk or other fabrics, also for tools having detachable blades. The feeding device is adapted to operate upon specially designed holders wherein the steel blanks are clamped, for either grinding, honing or stropping, before being fed forward to the respective machine.

The main object of my invention is to provide an automatic means for feeding holders containing a plurality of blanks from which safety razor blades or other straight edged tools are made through machines necessary to transform the blanks, thusly held, into finished sharpened tools. To this end the device is provided with an incline chute down which the holders gravitate sidewise until their movement is arrested, in which position they are in line with the guideway of the feeding device, and also with the selector which reciprocates back and forth in the direction of the length of the holder. The selector engaging the rear end of the lowermost holder, moves it forward until it is gripped by a pair of feed rolls located on opposite sides of the guideway. These rolls take the holder from the selector and moves it forward until it is engaged by a second set of feed rolls, which like the first, are located upon opposite sides of said guideway, but the latter pair are located nearer the machine to be fed. The function of the first set of feed rolls is not alone to strip the holder from the selector, but to close up any space that might exist between it and the preceding holders, because the feeding device is essentially a pushing feed, causing each successive holder to abut against the preceding one, thus forming a continuous feed through the device to the machine.

It will be noted that the first set of rolls being frictionally rotated, are free to slip when the holder being fed has caught up with the preceding one. The second set of rolls are practically positively driven and it is these rolls that determine the speed at which the holders are moved forward through the respective machine or machines, as the case may be.

Another object of my invention resides in the simple yet efficient feeding device for this purpose; first, of holding a plurality of blanks in strict alignment in a holder, secondly, of providing a chute of such size that a sufficient number of holders may be held as will keep the machine up to proper efficiency; and thirdly, having a selecting device capable of taking a plurality

of such holders one after the other, and introducing them successively to the rolls of the feeding device to advance them from said device to the particular machine or machines. Taking into consideration the necessity of having a stream of blade-laden holders constantly in reserve so that the device may feed a continuous unbroken line of holders through the desired machine.

A further object of the invention is the provision of means for selecting a holder from the stack, pass the same to a pair of constantly revolving feed rollers which relieves the selector of the same, and then passes the holder between a second set of constantly revolving feed rollers. Each holder as it is carried forward causes each preceding one to advance, forming an unbroken line as the holders and their contents are introduced to the respective machine or machines that complete the sharpening of the steel pieces. Further objects and advantages of my invention more or less broader than those hereinbefore stated will be partly obvious and in part specially pointed out. My invention, as at present preferred, will be more fully understood by reference to the drawings which illustrate merely an example of means for putting my invention into practice, and wherein:

Fig. 1 is a top plan view of my feeding device; Fig. 2 is a sectional view taken on line 2—2 of Fig. 1; Fig. 3 is another sectional view taken on line 3—3 of Fig. 1; Fig. 4 is still another sectional view taken on line 4—4 of Fig. 1; Fig. 5 is a sectional view taken on line 5—5 of Fig. 1, and Fig. 6 is a detail perspective of the holder showing the same as it passes through the feeding device to the machine, showing the guides in dotted lines, and Fig. 7 illustrates a modification of feed shown in Fig. 1.

It will be understood that my improvement is to be applied to a machine wherein blades of a given character are to be sharpened, honed or stropped, either by separate machines, or while going through a machine. The holders as they are discharged from the feeding device, each contact with the preceding one as they enter the machine, and they retain that pushing feed one against the other till they emerge at the discharge end of the machine, each blank in its respective holder having undergone the desired operation.

The machine itself into which the steel blanks are fed, forms no part of this application, therefore only the feeding device per se is shown. My holder for retaining steel blanks is shown herewith, but forms a separate application serially numbered 280,157; filed May 24, 1928. So much

of the holder only is shown as to give a general idea of its construction and arrangement, where-
 in the holder 80 has one jaw stationary with the
 body portion, while the jaw 79 is hinged to the
 5 body of the holder and is provided with a lock
 consisting of a pin engaging a spring 82 which
 holds the two members in clamped position. The
 edges of the pieces of steel extend beyond the top
 edge 78 of the holder. As the construction of the
 10 holders forms no part of this application only
 that portion is shown for a proper understanding
 of the same in connection with the device that
 has been designed to operate upon such holders
 and pass the same through the various machines
 15 to accomplish the objects for which they were
 designed, suffice to say that when the pieces of
 steel are inserted in the holder and the movable
 jaw closed upon them, they cannot possibly move
 therein while the holder is passing under the
 20 various means for giving the pieces a keen edge,
 after which they are discharged as a finished
 product ready to be finally inspected before being
 packaged for the trade.

25 My invention briefly described, comprises as
 above noted a feeding device for holders, each
 adapted to hold in locked position a plurality of
 blank steel blades, then feeding such holders to an
 incline chute where they will feed sidewise
 30 by gravity or otherwise one after another to a
 selector for passage thru the machine, it matters
 not, be it sharpening, honing or stropping.

35 Referring to Fig. 1, it will be seen that the platform or table 10 has suitable rectangular inclined arms 11 and 12, forming a skeleton chute, the latter extending transverse of the feed. The arms being so positioned as to feed the lowermost holder in the path of travel of selecting finger 13. A modification of this selecting means is shown in Fig. 7 wherein is provided an endless chain 85
 40 which operates over suitable wheels 83-84, the chain has suitably spaced thereon selecting fingers 13' which protrude through the slot in the table 10' and causes the lowermost holder 80 to be advanced from the stack. The means by which the reciprocating finger is operated will be fully described further on in this description.

45 As it is presupposed to do the work in quantities, as soon as the holder has been selected and introduced to the forward set of rolls, the same maintains such speed throughout the time it may be undergoing the particular operation of the machine, till it is discharged at the opposite end.

50 My feeding device comprises a power pulley 14, which may be operated by any motive power by which the machine may be driven. The pulley is secured to shaft 15, which is also provided with a worm 16 which is in contact with, and drives a gear 17 mounted to turn on a vertical shaft 18. To the upper end of this shaft is secured a gear 19 which meshes with a like gear 20 on a stud shaft 21. These gears are located below the level of the travel of the holders as they
 55 pass through the device.

60 As the holders are fed down the chute they come into contact with the slot 22, in which the finger 13 operates, the holder is passed forward between two sets of feed rolls 23, 24, 25 and 26, carried on stud shafts 27 and 28, the rolls 24 and 26 are secured in proper position with respect to the guideway 29, by means of a set screw 30, with a suitable lock nut 31 and 32, for keeping the roll in proper stationary relation to the holder as it passes. The rolls 23 and 25 are mounted in pivoted flexible housings
 70

33 and 34, and each have springs 35 and 36, suitably mounted to produce tension through the adjusting screws 37 and 38; the latter is provided with suitable lock nut 39 and 40 whereby to give the proper tension to the roller as the holder passes between the same. By having one flexible housing as described, the rolls are capable not only of adjusting itself to the holders, but the holders attain the peripheral speed of the rolls.

85 The shafts 27 and 28, each are provided with small gears 41 and 42, which mesh respectively with the main feed gears 19 and 20, while at the same time said rolls 23 and 24, are each provided with friction disks 43 and 44, which are applied above the rollers, and held in proper frictional contact therewith by suitable lock nuts 45 and 46. The pivoted housings 33 and 34, may be provided each with a limit stop 47 on the housing, and may abut against a like stop 48 on the adjusting screw 37. As above noted, any desired tension may be applied to the pivoted housings by means of their adjusting means, the pivoted housings 33' 34' carrying the feed rollers 24-26, by means of the adjusting screws 30 100 hold the rollers in proper feeding contact with the holders 80 as they pass between them. While the feed rollers 23-25 mounted in pivoted housings 33-34 by reason of their yielding means 35-36 are permitted to spread just the necessary distance to permit the proper feeding of the holder as it engages said rollers. It may be noted that the set of rolls 23 and 24, which are provided with friction washers, travel faster than the rolls 25 and 26 which are not so provided. 110 The purpose of this is to enable these auxiliary feed rolls to have the holders catch up one with the other so the feed through the machine they are about to enter may be entirely uniform and continuous. The feed rollers 25 and 26 being 115 positively driven by means of large gears 49 and 50, each meshing respectfully with gears 19 and 20, which when the holder is engaged by said rolls, the said holder is positively gripped between them and thereby advances the same with 120 proper speed to the machine.

125 Referring now to Fig. 3 wherein shaft 18 is seen properly housed in bearings 51 and 52 at its upper and lower ends. Suitably secured to the shaft 18 is a disk 53, having a friction face, and operates against a like disk 54, carried by the gear 55. The downwardly extending hub of the said gear may be provided with one member of a clutch 56, while immediately below the same is a hand wheel 57, the hub 58 forming the second member of the clutch. While below the hand wheel 57 on its lower side, is provided with a friction washer 59, the same being held in proper arrangement by a suitable hand adjusting nut 60. The friction arrangement at the lower end of the shaft 18, is for the purpose of disengaging the feed member, should one of the holders get caught in the device. This arrangement permits the selecting finger 13 140 to be moved back and forth without disturbing the rest of the mechanism.

130 From the above it will be seen that the power is transferred from the driving pulley 14 to the power distributing shaft 18, thence by reason 145 of the gear drive of the respective rolls with the main power drive, will cause the holders to be fed one by one between the rolls in rapid succession, as above noted, each abutting the other and pushing it out of the feeding device 150

into the machine. The feeding means above referred to will now be described.

Adjacent the gear 55 is mounted another gear 61, the latter having a stud shaft secured to the 5 lower part of the bracket. The gear 61 carries a crank arm 62 to which is secured a link 63. Under the table top 10 is a chamber 64 into which extends a shaft 65, the latter carries on its lower end an arm 66, which connects with the link 10 63, and causes motion to be imparted to the said shaft. To the upper end of said shaft 65, and operating in the chamber 64, an arm 67 having a slot 68 (shown in dotted lines). The selecting finger 13 is secured to a reciprocating member 15 69, operating between guides 70 and 71. A stud 72 carried by said reciprocating member 69, extends through the slot 68, and is provided with a lock nut 73 thereon to hold the respective parts together, so as to afford the utmost freedom of 20 the reciprocating member 69.

In line with the longitudinal movement of the selector finger 13 through the table top 10, is provided a guide 29 comprising side walls 74 and 75 (see Figs. 3, 4, and 6), with suitable toes 76 and 25 77, to engage shoulders on the holder, and hold the same securely in an upright position while passing through the feeding device. The holder when it is selected from the others in the chute, is conveyed along the continuous way from said 30 chute to the guide 29, the latter being provided with suitable openings at proper places for the engaging faces of the feed rolls 23, 24, 25 and 26 to make contact with the holder and assist its passage to the machine.

The operation of my automatic feeding device resides in having an inclined chute that is adapted to receive and hold a plurality of holders that were previously filled with pieces of steel that are to be sharpened. Each holder rests on the 35 inclined arms 11-12, which in cross section are angular, holding and guiding the holders to a position where they are engaged by the selector finger 13 and discharged in the direction of their length. As shown herein a reciprocating member engages the lower holder and moves the same forward until it is gripped by the first set of feed rolls 23-24. These rollers revolve at a faster speed than the selector finger 13 reciprocates, thus the rollers receive the holder 80 and pass 40 it along into the guideway 29, where it is again gripped by a second set of feed rollers 25-26. The feeding rollers 23-24 are only frictionally secured to their shafts (see Fig. 4) the nuts 45-46 securing the proper friction for the rollers. The 45 rollers 23-24 are driven from gears 19-20, which are directly driven from the main power shaft 15. The rollers 25-26 are driven by gears 49-50 on each side of the guideway 29, while each gear also meshes with the gears 19-20.

The shaft 18 which meshes with suitable gearing to the shaft 15, drives the various rollers at the desired speed, the shaft 15 being the power shaft distributes the power through the work 16, where it revolves the various rollers and the reciprocating selector in proper relation to each other to accomplish the desired result. A hand wheel 57 with its clutch and cooperating friction disks adapt the same to be manually adjusted or stopped if desired. As has been noted, the feed rollers 24-26, are rigidly held on their shafts in proper feeding contact with the movable holder as it passes along, while the other feed rollers 23-25 are yieldingly held in contact with the holders 80. The gear 55 on the shaft 18 drives a like gear 61 that causes the arm 63 to reciprocate

thereby causing a reciprocating movement to be transmitted to the block 69 carrying the selector finger 13, and at the same time imparts to the shaft 18 a much reduced speed.

Immediately above the reciprocating block 69 in the table 10 to which the selector finger 13 is secured and reciprocates in slot 86, is secured a stop bar 87 which the holders as they descend to be engaged by the selector are aligned with the guideway 29. Thus it will be seen that when rotation is imparted to the shaft 18, then to the gears, these in turn cause the feed rollers to rotate and pass the holders in a direction of their length through the guideway 29. It is to be understood that the feed of the rollers 25-26, is essentially a push feed, and it is this feeding action that causes each holder to contact with the one immediately preceding it, and causes it and those immediately forward of the same to move forward as an unbroken line through the 95 machine.

The main supporting casting 88 carries all the coating parts, and is provided with a depending leg 89 by which it may be attached to machine. To the center of this casting is an upright post 91 100 that supports the guideway 29. Below the casting 88 is secured a housing 90 that supports the main drive shaft, and the distributing driving means.

In accordance with the provisions of the patent statutes I have herein described and shown the principal form of my invention which I now consider, after experimenting with the same, as representing the best embodiment thereof, but I desire to have it understood that the device is 105 only illustrative and that the invention may be carried out in other ways than that shown and described, but all of which are intended to come within the scope of the claims.

Having thus fully described the invention, what 110 I claim as new and desire to secure by Letters Patent is:

1. In a holder feeding device of the character described, the combination with inclined arms 110 upon and down which the holders pass, a guide 120 for receiving each holder in turn from the arms to longitudinally align the same with the machine, a plurality of sets of rollers, arranged in series, friction means for driving the first set, a member adapted to select the lower holder and 125 pass it to the first set of frictionally driven feed rolls, a second set of feed rolls, means for positively driving the second set so that the holders will abut each other as they pass to the machine, and a guide for the holders interposed between the 130 rolls.

2. In an automatic holder feeding device of the character described, the combination of an inclined skeleton chute down which the holders are fed, an alignment device including a channel 135 for the holders as they emerge from the chute, a member operating within the channel for discharging the lower holder therefrom, a guide at the end of the channel, and feed rollers comprising successive frictionally and positively driven 140 elements rotatable at different speeds for advancing the holders in succession through the guide to a machine.

3. In a feeding device for holders of the character described in combination, a power shaft, a driven shaft at right angles thereto having a gear thereon, a supplemental shaft having a gear meshing with the first mentioned gear, one set of frictionally driven rolls pivotally mounted and 145 adapted to mesh with each of said gears, one of

- said rolls being spring pressed, a guide for the holders to pass them in proper position to be advanced to a machine, and a second set of positive driven rolls meshing with said gears where-
5 by they are advanced in end contact relationship with each other from the device to the machine.
4. In a feeding device of the character de-
scribed, a blade holder, selecting means for en-
gaging said holder, a plurality of feed wheels,
10 certain of which are frictionally driven and grip
said holder from the selecting means, and others
of which are positively driven and engage the
holder and move the same in feeding direction,
the rate of rotation of said first-mentioned
15 wheels being greater than that of said second-
mentioned wheels whereby a plurality of blades
may be uniformly and continuously presented to
finishing mechanism or the like.

5. In a device of the character described for feeding blade holders in an upright position, the combination of a reciprocating selecting means for advancing one holder after the other, of frictionally driven rolls for stripping each holder 80 in turn from the selecting means, other positively driven rolls for receiving and discharging said holders in end to end relationship in end contact with the next adjacent holder as it is discharged from the feeding device, and a guide 84 for the holders for retaining them in a predetermined path of movement, whereby the holders and blades are uniformly and consecutively fed in unbroken line to an abrading or like machine. 90

THEODORE G. McGIRR.
